UNITED STATES PATENT OFFICE.

LEWIS SYKES, OF CAMDEN, NEW JERSEY, ASSIGNOR, BY DIRECT AND MESNE ASSIGNMENTS, TO KELLER PNEUMATIC TOOL COMPANY, OF GRAND HAVEN, MICHIGAN, A CORPORATION OF MICHIGAN.

ECCENTRIC FOR PNEUMATIC TOOLS AND THE LIKE.

1,318,818.

Specification of Letters Patent. Patented Oct. 14, 1919.

Application filed October 30, 1918. Serial No. 260,237.

To all whom it may concern:

Be it known that I, LEWIS SYKES, a citizen of the United States, residing in the city and county of Camden, State of New Jersey, 5 have invented a new and useful Eccentric for Pneumatic Tools and the like, of which the following is a specification.

My invention relates generally to pneumatic drills or air tools, and consists particularly in a novel construction of an eccentric and driving mechanism therefor, and my object is to produce an eccentric of a strong and durable character in conjunction with a strong and durable coacting driving 15 connection, whereby the breakage which has heretofore been experienced in devices of this character, will be reduced to a minimum or entirely eliminated.

It is well known that pneumatic drills or 20 air tools and similar implements which are used in boiler-shops, shipyards, structural metal plants and the like, frequently receive very severe usage, as they are frequently operated by inexperienced and unskilled workmen, which results in the breakage 25 of various parts thereof, and my present invention is particularly designed to remedy defects heretofore existing particularly in the eccentric and driving connections common 30 to the eccentric and the crank shaft in pneumatic drills of the general character hereinabove referred to.

It has heretofore been the practice in 35 pneumatic drills or air tools of the general character to which my invention relates, to employ an eccentric for actuating the distribution valve, having a driving connection with the top of the crank shaft and to slot said eccentric across the top thereof in a 40 line at one side of the diameter thereof and parallel to said diameter. The presence of this slot reduced the strength of the eccentric body very materially, since a small arc-shaped area is formed at one side of said 45 top in proximity to the walls of which slot are located the flats or driving faces at the top of the crank shaft, whereby the eccentric is rotated and the proper reciprocations of the valve effected through the eccentric strap 50 and its adjuncts.

In this prior art construction, this small 55 arc-shaped area at one side of the eccentric top in practice becomes gradually spread apart or away by the continual pressure and vibration of the flats or driving faces on the

upper end of the crank shaft, thereby causing a slight expansion of the outer upper walls of the eccentric, thereby creating a clamping or binding action within the eccentric strap which connects the eccentric 60 to the distribution valve, which results in a breakage of the eccentric straps. This spreading action of the eccentric wall is caused by the driving portion of the eccentric being too short, which is formed by 65 the milling of the transverse slot in the top of the eccentric heretofore referred to, and, in addition, the flats or driving faces at the upper end of the crank shaft in the above-mentioned structure in a short time show 70 excessive wear and create this spreading action at the small arc-shaped area at one side of the slot in the top of the eccentric, which causes the eccentric to rise or jump away from its seat, thereby raising the eccentric straps and breaking the pins off the 75 end of the distribution valve, and in certain instances, I have found the clearance or play between the top of the eccentric and the under side face of the bonnet which forms 80 a closure for the top of the drill casing was sufficient to allow the eccentric to jump away from the driving seat for about half a revolution or more and then drop back again into the wrong position for time, so that 85 the timing of the throw of the valve was altered to such an extent that it will cause the drill to run backward.

In order to remedy the foregoing defects, I have devised a novel construction of an 90 eccentric having a strengthening boss on the top therof to take up any clearance between the top of the eccentric and the underside of the bonnet, which prevents the eccentric from jumping up and binding in the eccentric 95 strap, and in lieu of a slot extending all the way across and weakening the top of the eccentric, I broach a hole in the eccentric about three-quarters of its depth from the top downwardly, said broached hole terminating in a round bottom bearing, which is of lesser diameter than the top journal bearing of the crank shaft, the latter having a shoulder or abutment formed thereon upon which the eccentric rides. 100

The flats or driving faces at the top of the crank shaft are of the same contour as the hole through the eccentric and are prolonged to form an extended and durable bearing in the hole of the eccentric, which latter is de- 110

tachable therefrom, so that an abundance of material is provided in the proper place for both the crank shaft and the eccentric, both of which are thereby very much strengthened, so that breakage of the eccentric, spreading of the eccentric straps and breaking the valve pins, are not only reduced to a minimum, but will be found to be entirely obviated by my invention.

10 To the above ends my invention consists of a novel construction of a pneumatic drill or air tool having an eccentric of novel construction intermediate the distribution valve and the driving faces of the crank shaft.

15 It further consists in prolonging in a novel manner the driving faces common to the upper end of the crank shaft and the broached hole in the eccentric.

It further consists of a novel construction 20 of an eccentric having a boss on the upper portion thereof adapted to reduce clearance and to contact with the under surface of the bonnet, said boss and eccentric having a hole broached therethrough conforming to the 25 flats or driving faces of the upper end of the crank shaft.

It further consists of other novel features of construction, all as will be hereinafter fully set forth.

30 For the purpose of illustrating my invention, I have shown in the accompanying drawings one form thereof which is at present preferred by me, since the same will give in practice satisfactory and reliable results, 35 although it is to be understood that the various instrumentalities of which my invention consists can be variously arranged and organized and that my invention is not limited to the precise arrangement and organization 40 of these instrumentalities as herein shown and described.

Figure 1 represents a vertical, sectional view of an eccentric and in elevation the coacting driving portion of a crank shaft 45 embodying my invention, the pneumatic drill in conjunction with which my novel eccentric is employed being shown diagrammatically or in dotted lines.

Fig. 2 represents a side elevation, in detached position, of a portion of the upper end of a crank shaft, with my novel eccentric in section thereon.

Fig. 3 represents a perspective view of my novel eccentric in detached position.

55 Fig. 4 represents a bottom plan view of figure 3.

Fig. 5 represents in perspective the upper or driving end of the crank shaft, showing the elongated bearing or flats or driving faces 60 thereon coacting with my novel eccentric.

Similar numerals of reference indicate corresponding parts.

Referring to the drawings:—

1 designates the casing of a rotary pneu-

matic drill, which is provided with the 65 piston cylinders 2, in which reciprocate the pistons 3, which are connected by means of piston rods 4 with a crank shaft 5, which is intergeared with a spindle 6, which receives the drill, reamer or other working 70 tool, the foregoing elements being of any standard conventional type, so that a further detailed description thereof is unnecessary.

7 designates a bonnet, which may also be 75 of any conventional type and is secured to the casing 1 in any desired manner. The crank shaft 5 at its upper end terminates in the journal 8, which revolves in a suitable ball-bearing and has the round bearing 9 80 of lesser diameter above it, thereby forming a shoulder or abutment 10, on which my novel eccentric hereinafter referred to rests.

The top or end extension 11 of the crank shaft 5 constituting the driving member 85 thereof for the eccentric, is faced off to produce the parallel flats or driving faces 12, which terminate at the shoulders 13, said driving faces extending about three-quarters of the way through the eccentric 14, which 90 has the holes 15 therein to lighten it. The eccentric 14 consists of a cylindrical block having eccentrically positioned in it, the hole 16, which is broached therethrough, the top of the eccentric having an annular boss 17, 95 through which said hole 16 extends, said boss 17 being adapted to be seated in a recess 18 in the underside of the bonnet 7. The hole 16 at its lower end terminates in an annular recess or seat 19, which fits over the annular bearing 9 above the crank shaft journal 8 when the parts are assembled as seen in Figs. 1 and 2.

The eccentric 14 is engaged by an eccentric strap 20 of the usual construction, which 105 actuates the distribution valve 21, which controls in the usual manner the admission and exhaust of motive fluid to actuate the pistons and thereby the crank shaft.

It will be seen that when the parts are 110 assembled, the boss or annular bearing 17 preferably contacts with or is seated against the underside of recess 18 of the bonnet 7 and the bottom of the eccentric rests on the shoulder 10 above the journal 8 of the 115 crank shaft, so that any up and down play of the eccentric on the flats or driving faces 12 of the crank shaft is practically eliminated.

It will be seen from the foregoing, that 120 the provision of the eccentric boss 17 gives greatly added strength to the eccentric body and particularly the upper portion of the eccentric, and if for any reason a little clearance between the top of the eccentric and 125 the under side of the bonnet 7 must be allowed, said boss suffices to take up this clearance or reduce it to a minimum, which

will prevent the eccentric from jumping up and binding, clamping or breaking the eccentric strap.

By broaching the hole 16 in the eccentric, 5 having the rounded end walls 23 and the parallel flats or driving faces 22 and extending said hole about three-quarters of the distance from the top of the boss 17 downwardly and making the flats or driving faces 10 12 correspondingly elongated, as will be understood from Figs. 1, 2 and 5, an abundance of material is provided in the proper place and there is no liability of the eccentric body spreading under any conditions so 15 as to cause binding or breaking of the eccentric straps, nor can the eccentric rise away from its seat 10, or raise the eccentric straps or break the pins off the ends of the distribution valve, as is evident.

20 It will be apparent that when the bonnet 7 is removed, the eccentric 14 which is detachable vertically from the driving faces 12 of the crank shaft, can be readily slipped off upwardly from said driving faces for 25 the purposes of inspection, replacement or repair.

I have deemed it unnecessary to describe in detail the cycle of operation of the pneumatic drill, *per se*, as the same will be apparent to those skilled in the art, it being understood that the distribution valve controls the flow of the motive fluid to the cylinders 2, whereby the pistons 3 are reciprocated, the reciprocations of the piston actuating the crank shaft, the lower end of which transmits power to the spindle 6, while the upper end of said crank shaft rotates the eccentric 14 in the manner described, said eccentric controlling the reciprocations of said valve 21.

For the sake of clearness, I have shown the elements which constitute the novel features of my invention in full lines, the old structure of the prior art, as in Fig. 1, being 45 shown dotted.

It will now be apparent that I have devised a novel and useful construction of an eccentric for pneumatic tools and the like, which embodies the features of advantage 50 enumerated as desirable in the statement of the invention and the above description, and while I have, in the present instance, shown and described a preferred embodiment thereof which will give in practice satisfactory and reliable results, it is to be understood that the same is susceptible of modification in various particulars without departing from the spirit or scope of the invention or sacrificing any of its advantages.

60 Having thus described my invention, what I claim as new and desire to secure by Letters Patent, is:—

1. In a pneumatic drill or air tool, a cas-

ing, a bonnet therefor, a piston driven crank shaft in said casing, an eccentric detachably 65 mounted on an end of said crank shaft and having an eccentrically positioned boss on the top thereof adapted to seat against the under side of said bonnet, there being a hole extending through said boss and eccentric to 70 a point near the bottom of the latter, to form an elongated bearing for the driving portion of said crank shaft, and means actuated by said eccentric to control the admission of motive fluid to said drill. 75

2. In a pneumatic drill or air tool, a crank shaft, means for actuating the latter, a journal bearing on the upper end of said crank shaft, a round bearing of lesser diameter above said journal bearing, thereby 80 forming an eccentric supporting shoulder, the top of said crank shaft being provided with flats or driving faces, an eccentric adapted to rest on said shoulder and having an eccentrically located boss on the top 85 thereof, said eccentric having a hole broached through said boss and body into a seat in the bottom of said body, the contour of said hole corresponding to the contour of the driving faces at the top of said 90 crank shaft, and means for the distribution of the motive fluid controlled by said eccentric.

3. In a pneumatic drill or air tool, the combination of a crank shaft having an 95 upper journal bearing 8, a bearing 9 above said journal bearing of lesser diameter, forming the eccentric supporting shoulder 10, the top of said crank shaft terminating in the flats or driving faces 12, with an eccentric resting on said shoulder and detachable therefrom, and having a bottom seat 19 to receive said crank shaft bearing 9, said eccentric having the eccentric boss 17 on the top thereof and the hole 16 therein extending through said boss downwardly to said bottom seat 19, said eccentric hole having the flats or driving faces 22 and the portion of said crank shaft flats 12 engaging said faces 22 occupying about three-quarters of 110 the thickness of said eccentric.

4. As an improved article of manufacture, an eccentric for a pneumatic drill or air tool, composed of a body having an eccentric boss 17, at the top thereof, said body having at the bottom thereof an annular seat 19 and a hole 16 therein extending from the top of said boss through said boss and body to said seat, said eccentric hole having the flat driving faces 22 adapted to coact with similar driving faces of a crank shaft. 120
